CONTAINER FOR FOODSTUFFS OR THE LIKE

Albert Kner, Chicago, Ill., assignor to Dart Industries,
Inc., a corporation of Delaware

Filed Apr. 1, 1968, Ser. No. 11,234

Term of patent 14 years

Int. Cl. D7—01

U.S. Cl. D44—10

FIG. 1

FIG. 2

FIG. 3

FIG. 4

FIG. 5

FIG. 6

FIG. 7

FIG. 8

FIGURE 1 is a perspective view of a container for foodstuffs or the like, showing my new design;

I claim:

The ornamental design for a container for foodstuffs or the like, substantially as shown.
